UNITED STATES PATENT OFFICE.

AUGUST H. KATTERJOHN, OF DENVER, COLORADO, ASSIGNOR, BY MESNE ASSIGNMENTS, TO THE GARDNER-DENVER COMPANY, OF QUINCY, ILLINOIS, A CORPORATION OF DELAWARE.

LUBRICATOR FOR ROCK DRILLS.

Application filed April 17, 1923. Serial No. 632,779.

The present invention relates to means for lubricating the various moving parts of rock drills, and the object is to provide a mechanism which will properly distribute the necessary amount of lubricant throughout the machine and to the parts subject to wear, said mechanism avoiding excessive supply, and consequent waste of the lubricant.

In the accompanying drawings:—

10 Figure 1 is a longitudinal sectional view through a rock drill equipped with the lubricator,

Figure 2 is a sectional view on the line 2—2 of Figure 1,

15 Figure 3 is a detail sectional view of the throttle and distributing valves,

Figure 4 is a longitudinal sectional view through the throttle valve and taken on the line 4—4 of Figure 3,

20 Figures 5, 6 and 7 are cross sectional views taken respectively on the line 5—5, 6—6 and 7—7 of Figure 4,

Figure 8 is a detail sectional view on the line 8—8 of Figure 1 and Figure 2,

25 Figure 9 is a cross sectional view substantially on the line 9—9 of Figure 1.

In the embodiment disclosed, a drill actuating motor is provided, consisting of a cylinder member 10 containing a piston chamber 11, in which a reciprocating piston 12 is located. The front end of the cylinder member is in the form of a mounting designated generally by the reference numeral 13, and containing a rotatable drill-steel receiving

30 chuck 14 that may be of any well known character. This chuck is rotated in a well known manner by means of a motor, mounted on the front end of the cylinder member, the casting of which is shown at 15, said motor driving a worm shaft 16 geared, as shown at 17 to the chuck.

35 Expansible motive fluid, such as air, is supplied to the chuck or drill actuating motor through a suitable coupling element 18 on the rear end of the cylinder member. This coupling element is located at one end of a tapered valve seat 19, in which is located a rotatable tapered throttle valve 20. The valve is chambered, as shown at 21, and has an open end at the coupling. A passageway

22, leading from the tapered valve 19, is in communication with a distributing valve cage 23 containing an automatic reciprocating distributing valve 24 that governs the passage of the fluid to the piston chamber 11 on opposite sides of the piston 12, for the purpose of reciprocating the same in a manner well known to those skilled in the art. Communication between the motive fluid and the passageway 22 is controlled by the throttle valve 20, which has a lateral port 25 opening into its interior chamber 21 and movable into and out of communication with the passageway 22.

40 The supply to the chuck rotating motor 15 is directed by a conduit 26, indicated in Figures 1 and 2, and a portion of which is illustrated in Figure 5. Communication between the motive fluid supply and the conduit 26 is controlled by the rotary throttle valve 20, which has a port 27 movable into and out of register with the conduit 26 and opening into the interior chamber 21 of said valve.

45 So far as thus described, the structure is intended to be typical of rock drills, and no claims are herein made thereto, the invention residing in the means for lubricating a drill as hereinafter described.

50 Formed in one side of the cylinder member 10 is a longitudinally disposed elongated lubricant reservoir 28, having a filling nipple 29 closed by a plug 30. A single combined motive fluid supply and lubricant outlet passageway 31 is provided, having a port 32 at its inner end opening into a valve chamber 33 formed at one side of the reservoir. Spaced ports 34, located on opposite sides of the port 32, extend from the same end of the valve chamber 33 to the lubricant reservoir, one opening into the lower portion of said reservoir, the other into the upper portion thereof, as illustrated in Figure 1. The rear end of the passageway 31 has a transverse portion 35 communicating with a port 36 that opens into the throttle valve chamber 19, as illustrated in Figures 4 and 5. The throttle valve 20 has a longitudinal channel 37 in one side that is movable into and out of communication with the port 36, and a port 38 in said valve and opening into the interior

chamber 21, communicates with the channel 37. By comparing Figures 4, 5, 6 and 7, it will be noted that when the throttle valve 20 is open, or in other words, when the main supply port 25 is in communication with the passageway 22, leading to the drill actuating motor and the port 27 is in communication with the conduit 26 leading to the drill rotating motor, so that motive fluid is being supplied to these motors for operating them, the channel 37 is in communication with the port 36 and consequently fluid under pressure will traverse the passageway 35 and 31, so that fluid under pressure will be in the chamber 33, and passing through the ports 34 will put the oil in the reservoir 28 under pressure. The port 32 is normally covered by a ball valve 39 located in the chamber 33, and seated upon the inner end of said port 32 where it is urged by a coiled spring 40 bearing against the ball and against the closure plug 41.

In the operation of the drill, however, a material amount of vibration takes place, and as a consequence the ball valve 39 is rocked laterally on its seat so that the port 32 is considerably open. This vibration also seems to cause the oil in the reservoir 28 to be churned and practically vaporized. Moreover a pulsation of motive fluid is created in the internal chamber 21 of the throttle valve. This pulsation evidently occurs also in the passage 36-35 and 31, so that the vaporized oil carried by the air, finds its way back through the said passageway and through the channel 37 and port 38 until it enters the air stream, flowing into the motor. This delivery, it will be observed, takes place in advance of the branches 22 and 26 of the main supply leading to the respective motors, so that the air flowing to said motors carries the lubricant with it, and such lubricant is distributed over the working parts.

In order to lubricate the rotating chuck 14 and the gearing 16 and 17, a passageway 42 opens into the rear end of the chuck chamber and communicates at its rear end through a port 43 with one end end of a valve chamber 44. This valve chamber has a port 45 opening into the end of the lubricant reservoir. A ball valve 46 normally seated over the port 43 and held by a spring 47, will obviously be vibrated by the longitudinal vibration of the motor, so that a modicum of the vaporized oil will be permitted to pass to the chuck chamber and will be distributed over the bearing portions thereof and on the gearing.

The drill above described, and as shown in Figure 9 is mounted to slide in a guide shell 48, said motor having slide flanges 49 operating in guideways 50 in a manner well understood. This motor is moved in the usual manner by a screw 51 and the main exhaust port from the piston chamber 11 is in the

underside of the same as illustrated at 52, being centered over the screw 51. As a consequence the oil-laden exhaust fluid passing through the port 52, will impinge against the screw 51, and a film of oil will be deposited on said screw so that it and its bearing in the nut 53 of the motor will be lubricated. Moreover the exhaust will prevent the accumulation of dirt and grit upon the screw. In order that this exhaust will not pass rearwardly and prove an objection to the operator, of the drill behind the same, a transverse shield flange 54 is carried by the motor in rear of the exhaust port 52, and substantially fills the space within the shell 48 below the motor.

From the foregoing, it is thought that the construction, operation and many advantages of the herein-described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. In a lubricating system, the combination with a vibratory motor of a lubricant reservoir that vibrates with the motor, a motive fluid supply means for the motor, a passageway for admitting fluid to the reservoir and permitting the passage of lubricant from the reservoir, a valve chamber with which the passageway communicates, a plurality of ports between the valve chamber and different portions of the reservoir, a valve normally closing off the communication between the passageway and chamber, and means for yieldingly holding the check valve in its position to close the port.

2. In a lubricating system, the combination with a vibratory motor, of a lubricant reservoir that vibrates with the motor, a motive fluid supply means for the motor, a passageway leading from the motive fluid supply to the reservoir for admitting fluid to the reservoir, and permitting the passage of lubricant from the reservoir, a valve chamber with which the passageway communicates, spaced ports between the valve chamber and the upper and lower portions of the reservoir and located on opposite sides of said communication, and a valve in the chamber normally closing off the said communication.

3. In a lubricating system the combination with a vibratory motor comprising a cylinder member having a piston chamber and a piston therein, of a motive fluid supply passageway leading from the motive fluid supply to the reservoir, communicating with the piston chamber, a rotary throttle valve controlling the passageway, a lubricant reser-

voir, a fluid supply and lubricant outlet passageway opening into the motive fluid supply passageway through the throttle valve and controlled by the latter, a valve chamber with which said second passageway communicates, said chamber having communication with both the upper and lower portions of the lubricant reservoir, and a check valve movably mounted in the chamber and controlling the communication of said second passageway only therewith, said valve being vibrated from its seat with the vibration of the motor.

4. In a lubricating system, the combination

with a vibratory motor and a lubricant reservoir, of means for establishing communication between the two, comprising a chamber vibrated by the motor, a passageway between the motor and reservoir, a valve in said chamber controlling such passageway and vibrated from its seat by the vibration of the motor, and a plurality of open ports between the chamber and the upper and lower portions of the reservoir.

In testimony whereof, I affix my signature.

AUGUST H. KATTERJOHN.
